[57] CLAIM

The ornamental design for an insulated jar with lid, as shown.

DESCRIPTION

FIG. 1 is a top plan view of an insulated jar with lid showing our new design;

FIG. 2 is a fragmentary section taken on the line II—II in FIG. 4.

FIG. 3 is a side elevational view thereof;

FIG. 4 is a bottom plan view thereof; and

FIG. 5 is an exploded front or rear elevational view thereof.
